(57) **CLAIM**

The ornamental design for a portable defibrillator case, as shown and described.

DESCRIPTION

FIG. 1 is an upper perspective view of the portable defibrillator case showing my design.

FIG. 2 is a front elevation view thereof;

FIG. 3 is a rear elevation view thereof;

FIG. 4 is a side elevation view thereof;

FIG. 5 is an opposite side view thereof;

FIG. 6 is a top plan view thereof;

FIG. 7 is a bottom plan view thereof;

FIG. 8 is another perspective view thereof, showing an open position of the case; and,

FIG. 9 is still another upper perspective view thereof, showing an attachment of a stand.

The broken line portions of FIGS. 1, 2, 8 and 9 are presented for illustrative purposes only and form no part of the claimed design.
